D10-129. OR D 18,723 EX

DESIGN.

—o—

C. W. WARD.

WATCH BRIDGE.

No. 18,723.

Patented Nov. 6, 1888.

UNITED STATES PATENT OFFICE.

CHARLES WILLIS WARD, OF YONKERS, NEW YORK.

DESIGN FOR A WATCH-BRIDGE.

SPECIFICATION forming part of Design No. 18,723, dated November 6, 1888.

Application filed September 10, 1888. Serial No. 285,080. Term of patent 7 years.

To all whom it may concern:

Be it known that I, CHARLES WILLIS WARD, a citizen of the United States, residing at Yonkers, in the county of Westchester and State of New York, have invented and produced a new and original Design for a Watch-Bridge; and I do hereby declare the following to be a full, clear, and exact description of the same, reference being had to the accompanying drawing, forming a part thereof.

My invention relates to a new and original design for outer plates or bridging for watches; and it consists in the peculiar formation and ornamental shaping hereinafter described and claimed.

In the accompanying engraving the outer casing or rim of the works is represented at A. That portion of the plate or bridging located at the bottom and extending up the side, which is usually termed the "barrel-bridge," is represented at B. This portion B is formed on its outer edge to conform to the inner contour of the casing. Commencing at the terminus of the lower edge on the left, the edge is curved outwardly for a short distance and then inwardly and terminates in an angle or corner. From this corner the upper edge is recessed or curved downward for a short distance, and is there carried vertically upward and finally in graceful, irregular, and nearly horizontal curves to the side or casing. The upper portion, or what is usually termed the "train-bridge," is arranged to occupy the entire upper portion of the casing, its outer edge fitting the inner side thereof. This portion is represented

at C, and extends downward, its lower end forming a rounded apex and coming directly over the center of the watch. The sloping sides of this portion C are formed in a series of graceful and sweeping curves extending inwardly and outwardly from the outer extremities of the upper edges to the apex. The lower right-hand edge is irregularly curved and conforms to the opposite of the adjacent curve of the lower bridge, there being a narrow intervening space with parallel sides extending from near the center to the outer edge of the watch. A double curve is formed on the right of the apex of the portion C, as shown. The balance-cock D, which is formed in substantially the shape usual to this portion, is located at the lower left-hand side of the watch, its lower extended end being placed in the recess formed by the curving of the portion B, a narrow space intervening. By this arrangement and shaping it will be seen that the balance-wheel and a portion of the "train" are disclosed and that the general appearance is beautified and improved.

Having thus fully described my invention, what I claim as new, and desire to secure by Letters Patent, is—

The design for a watch-bridge, substantially as herein shown and described.

In testimony whereof I affix my signature in presence of two witnesses.

CHARLES WILLIS WARD.
